UNITED STATES PATENT OFFICE.

VICTOR S. PEARLMAN, OF CHICAGO, ILLINOIS.

DESK LAMP.

Application filed May 13, 1925. Serial No. 29,877.

This invention relates to improvements in desk or table lamps and has for its principal object to provide a new and improved construction wherein a lamp may be completely concealed beneath the upper surface of a table or desk but may be brought into operative position by vertical movement of the lamp body. Other objects of the invention will appear from time to time as the following description proceeds.

The invention may best be understood by reference to the accompanying drawings, in which

Figure 1 is a view in perspective of a desk to which my invention has been applied.

Figure 2 is an enlarged sectional view of the desk and lamp shown in Figure 1 but with the lamp body lowered so as to be invisible from the top of the desk with the exception of the top of the lamp, which is flush with the upper surface of the desk.

Figure 3 is a view in cross section taken on line 3, 3 of Figure 2.

Figure 4 is a modified form of my invention in which vertical movement of the lamp is controlled by frictional devices cooperating with the guide means.

Figure 5 is a detailed section showing the adjusting devices associated with the vertical guides.

Figure 6 is a detailed view showing one form of locking mechanism which may be used in connection with my improved device, and

Figure 7 is a detailed view showing the hinged sides of the lamp, and a pen receptacle formed in the top of the lamp body.

Referring now to the details shown in the drawings, the invention is shown as applied to a desk or table 10 of any suitable form. A lamp body 11 consists of a shade 12 having a flat top 13, the shade preferably being rectangular in form and open at the bottom so as to shed the rays of the light from a lamp 14 in a downwardly direction as clearly shown in Figure 2. The front and rear sides 15, 15 of the shade are hinged along their upper edges, as shown in Figure 7, so as to be movable outwardly and thus permit the light to spread over a greater area, as desired, when the lamp is in raised position.

The lamp body is provided with suitable supports herein consisting of two vertically disposed members 16, 16 connecting opposite ends of the lamp body to a horizontally

disposed base plate 17. The lamp body and base plate 17 with the intervening supports 16, 16 constitute a unitary structure arranged to be moved vertically with respect to the top 20 of table or desk 10. An aperture 21 is formed in the top 20, this aperture being of such shape and size that the base plate 17 will fit closely in said aperture when said lamp is in raised position as shown in Figures 1 and 4, and when in closed position, as shown in Figure 2, the top 13 of the lamp body will fit snugly in said aperture flush with the upper surface 22 of the table top 20. In order to insure close fitting engagement, I provide a metallic frame 25 surrounding the aperture 21, this frame having chambered inner edges 26, 26 inclined downwardly and outwardly so as to be engaged by the inclined lateral margins 17^a of the base plate 17, and thus limit upward movement of the latter when it is raised into its uppermost position, as shown in Figure 1.

The upper plate 13 of the lamp body is preferably overhanging and provided with downwardly extending surfaces 27, 27 around its periphery adapted to engage and be guided into the upper margins of the frame 25 when the lamp is lowered into its collapsed position, as shown in Figure 2.

Guiding and supporting means for the lamp body and its associated movable parts are provided beneath the table top 20. In the form shown in Figures 2 and 3, this guiding and supporting means comprises a pair of vertically disposed rods 30, 30 spaced apart and suitably supported on L-shaped members 31, 31 and 32, 32 connected with a casing 33, suspended from the lower surface 95 of the desk top within which the lamp is adapted to be lowered. A pair of brackets 35, 35 are connected to extensions 36, 36 on the bottom of the base plate 17, which extensions preferably consist of cylindrical prolongations of the lamp supports 16, 16 having said brackets vertically adjustable thereon by means of lock nuts 60 and 61, threaded on said extensions. The brackets 35, 35 extend laterally from said extensions and are 100 provided with sleeve members 37, 37 slidably engaged on the supporting rods 30, 30.

In the form shown in Figures 2 and 3, means are provided for counterbalancing the lamp body comprising a pair of weights 110 40, 40 arranged to slide vertically on guide rods 41, 41 and each connected to an adja-

cent bracket 35 in opposite ends of the casting 33, by a cord 42 trained over a pulley 43, mounted on the adjacent upper guide rod 41, supporting member 31. The weights 40, 40 are preferably of sufficient mass to normally maintain the moving parts of the lamp in raised position. The lamp body may then be depressed by hand into closed position as shown in Figure 2. Means are provided for retaining the lamp in its depressed position comprising a spring pressed latch 45 extending through the frame 25 at the forward margin thereof and engaging a depression 46 formed adjacent the upper margin of the lamp top 13, as shown in detail in Figure 6. Means are provided for releasing this latch, in the form shown consisting of a lever 47 pivoted on an arm 48 secured beneath the table top 20 and controlled by a rod 49 extending forwardly to a spring pressed button 50 placed at readily accessible position, as, for instance, in front of the table or desk as shown in Figure 1.

Means are provided for limiting the downward movement of the lamp body so as to maintain the top of the lamp 13 flush with the upper surface of the table top 20 when the lamp is depressed. In the form shown, this means comprises a pair of nuts 55, 55 mounted on the threaded lower end portions 56, 56 of the upright guide rods 30, 30 and adapted to engage the lower ends of the sleeves 37. These nuts may be adjusted to the proper positions to accommodate the device to various thicknesses of table tops with which it may be used.

The lock nuts 60 and 61 hereinbefore described, may be adjusted to insure the desired limiting engagement of the base member 17 with the frame 25 when the lamp is in raised position, these lock nuts 60, 61 being threaded on each extension 36 below the plate 17 and engage opposite sides of the bracket 37 so as to adjust the plate 17 with respect to said supporting bracket 37. Access to these adjusting nuts is afforded through the casing 33 by means of a cover 62 hinged at 63, as shown in Figure 2. A flexible lamp cord 64 of the usual form extends from the lamp through one of these lamp supports 16, and thence through an aperture 64a in the casing, as for instance, through the hinged cover 62.

Figures 4 and 5 show a modified form of my invention in which the counterbalancing parts are omitted and the vertical movement of the lamp is controlled manually in conjunction with friction devices engaging the guide rod 30. As shown in detail in Figure 5, the friction means comprises packing 65, 65 inserted in glands 66, 66 at opposite ends of the sleeve 37 and secured therein by threaded caps 67, 67. Said caps may be adjusted to provide the desired tension upon the guide rod 30. In other respects the

parts are the same as that already described in connection with the form shown in Figures 2 and 3. It will be noted that in the case of adjustment of the cap 67, however, a slight readjustment of the nut 55 on the lower end of the rod 30 may be necessary in order to compensate for change in position of the cap 67 in order to retain the desired flush relationship of the lamp top 13 with the table top 20. A handle 69 is provided at the top of the lamp body, this handle being of the usual flush hinge type and necessary to be raised into operative position as shown only when withdrawing or raising the lamp into operative position as shown in Figure 4.

Figure 7 also shows a pen holding receptacle 70 applied to the top of the lamp body 11 which is covered by the hinged lid 71. Manifestly, this receptacle will be accessible either when the lamp top is raised or lowered, and when in the latter position, the hinged lid will be flush with the adjacent table top. The base portion 17 may have a plain upper surface as shown in Figure 1, or may be provided with an inkwell and pen holder 75 as indicated in dotted lines in Figure 2 which will be invisible and inaccessible, excepting when the lamp is in raised position.

I claim:

1. In combination with a table having a top, a movable unit comprising a lamp body having a substantially plain upper surface, a plurality of supporting devices extending below said lamp body and connected to a horizontally disposed base plate to form a flat surface directly beneath and spaced vertically from said lamp body, and guiding means below the upper surface of said table and bracket devices carried by said movable unit, and engaging said guiding means to permit said lamp body to be raised above the upper surface of said table in one position with said base plate substantially level with said table top and to be lowered with the upper surface of said lamp body substantially flush with the upper surface of said table top in a second position.

2. In combination with a table having a top, a movable unit comprising a lamp body having a substantially plain upper surface, a plurality of supporting devices extending below said lamp body and extending through a horizontally disposed base plate forming a flat surface directly beneath and spaced vertically from said lamp body, guiding means below the upper surface of said table, bracket means connected to the lower ends of said supporting devices and co-operating with said guiding means to permit said lamp body to be raised above the upper surface of said table in one position with said base plate substantially level with said table top and to be lowered with the upper

- surface of said lamp body substantially flush with the upper surface of said table top in a second position.
3. In combination with a table having a top, a movable unit comprising a lamp body having a substantially plain upper surface, supporting means extending below said lamp body, and a horizontally disposed base plate connected to said supporting means and spaced vertically from said lamp body, guiding means below the upper surface of said table and co-operating with said movable unit to permit said lamp body to be raised above the upper surface of said table in one position with said base plate substantially level with said table top and to be lowered with the upper surface of said lamp body substantially flush with the upper surface of said table top in a second position,
- 10 and a casing below said table top forming a receptacle for said movable unit when the device is in lowered position, said guiding means comprising vertically disposed guide members disposed laterally of the path of movement of said movable unit at opposite ends of said casing and connected thereto.
4. In combination with a table having a top, a movable unit comprising a lamp body having a substantially plain upper surface, supporting means extending below said lamp body and a horizontally disposed base plate connected to said supporting means and spaced vertically from said lamp body, guiding means below the upper surface of said table and co-operating with said movable unit to permit said lamp body to be raised above the upper surface of said table in one position with said base plate substantially level with said table top and to be lowered with the upper surface of said table top in a second position, and counterbalancing devices below said table top connected to said movable unit.
5. In combination with a table having a top, a movable unit comprising a lamp body having a substantially plain upper surface, supporting means extending below said lamp body and a horizontally disposed base plate connected to said supporting means and spaced vertically from said lamp body, guiding means below the upper surface of said table and co-operating with said movable unit to permit said lamp body to be raised above the upper surface of said table in one position with said base plate substantially level with said table top and to be lowered with the upper surface of said lamp body substantially flush with the upper surface of said table top in a second position,
- 15 counterbalancing devices below said table top connected to said movable unit, and a casing below said table top forming a receptacle for said movable unit, when the latter is in lowered position, and enclosing said guide and counterbalancing means.
6. In combination with a table having a top, a movable unit comprising a lamp body having a substantially plain upper surface, supporting means extending below said lamp body, and a horizontally disposed base plate connected to said supporting means and spaced vertically from said lamp body, guiding means below the upper surface of said table and co-operating with said movable unit to permit said lamp body to be raised above the upper surface of said table in one position with said base plate substantially level with said table top and to be lowered with the upper surface of said lamp body substantially flush with the upper surface of said table top in a second position, counterbalancing devices below said table top connected to said movable unit and tending to raise the latter, and latch means adapted to selectively restrain said unit in lowered position.
7. In combination with a table or the like having a top, a movable unit comprising a lamp body having a substantially plain upper surface, supporting means extending below said lamp body, and a horizontally disposed base plate connected to said supporting means and spaced vertically from said lamp body, guiding means below the upper surface of said table and co-operating with said movable unit to permit vertical movement of said unit relative to said table top, a shade for the side of said lamp body and means permitting angular adjustment of said shade when the lamp body is in raised position.
8. In combination with a table having a top, a movable unit comprising a lamp body having a substantially plain upper surface, supporting means extending below said lamp body and a horizontally disposed base plate connected to said supporting means and spaced vertically from said lamp body, guiding means below the upper surface of said table and co-operating with said movable unit to permit vertical movement of said unit relative to said table top and a shade for the sides of said lamp body, and hinged thereto to permit angular adjustment of said shade when the lamp body is in raised position.
9. In combination with a table having a top, a movable unit comprising a lamp body having a substantially plain upper surface, supporting means extending below said lamp body and a horizontally disposed base plate connected to said supporting means and spaced vertically from said lamp body, guiding means below the upper surface of said table and co-operating with said movable unit to permit said lamp body to be raised above the upper surface of said table in one position with said base plate substantially level with said table top and to be lowered with the upper surface of said lamp body substantially flush with the upper surface of said table top in a second position,

substantially flush with the upper surface of said table top in a second position, said guiding means comprising a vertically disposed guide member offset laterally from the path of movement of said movable unit and means slidably connected with said guide member and extending laterally from below said base plate, and means permitting vertical adjustment of said last named means relative to said movable unit.

10. In combination with a table having a top provided with an aperture, a movable unit comprising an upper member, intermediate supporting means and a base, said upper member and said base both being adapt-

ed to have close fitting engagement in said table aperture, guiding means below said table top and co-operating with said movable unit to permit limited vertical movement of said unit relative to said top, means 20 permitting vertical adjustment of said base relative to said guiding means, and a casing below said table top forming a closed receptacle for said guiding means and said movable unit, and having means permitting access to said adjusting means when said movable unit is in lowered position.

Signed at Chicago, Ill., this day of May 8th, 1925.

VICTOR S. PEARLMAN.
